SKEWING ARRANGEMENT FOR GANTRY FRAMES

Robert W. Crist, Cleveland, Ohio, assignor to The Wellman Engineering Company, Cleveland, Ohio, a corporation of Ohio

Application October 8, 1943, Serial No. 505,489

7 Claims. (Cl. 105—179)

This invention relates to a skewing arrangement for the gantry frames of ore unloaders, cranes, hoists, traveling trolleys, and the like, where it is necessary or desirable to move either end of the frame on the track while the other end is held stationary or to move either end at a faster or slower speed than the opposite end is moved.

The principal object of the invention is to provide a skewing arrangement for gantry frames with provision for compensating for the relative foreshortening of the center line of the frame as compared to the track gauge, said arrangement being adapted for any stiff leg gantry frame.

Occasionally the tracks of an unloader opposite a boat to be unloaded are on a curve so that the stiff leg gantry frame is not in line with the hatch of the boat, making it necessary to provide complicated mechanism to bring the superstructure of the unloader in line with the hatchway. It is one of the objects of the present invention to be able to skew the gantry frame by a simplified mechanism so that the frame of the unloader can be readily brought into alignment with the hatch of the boat.

It frequently happens that the distance between the rails of the runway on which the unloader, crane, etc. runs does not remain constant but may shift to a greater or lesser span due to loads, soil conditions, etc., and it is a further object of this invention to provide a stiff frame with its traveling wheels, trucks and sills arranged in a manner to compensate for this variation in runway span, thus eliminating excessive wear on the flanges of the track wheels and rail heads, and preventing derailment or, if not derailment, undue stresses in the stiff frame.

A further object of the invention is to provide an independent drive with control for each end of the machine, thus eliminating the necessity of providing and maintaining a line or "squaring" shaft with its attendant gears, brackets, couplings, etc. extending across the full length of the stiff frame to connect to the track wheels at each end.

A still further object is to eliminate all motors, control and machinery (aside from the motors of the independent drive for each end of the machine) for skewing where skewing is necessary or desirable, since the skewing motion is accomplished by the travel motors through the controlled unequal movements of the ends of the frame. Thus the travel motors serve a dual purpose.

In the drawings I have shown a simplified ap-

plication of the invention, the gantry frame shown being adaptable for any of the purposes mentioned above, it being understood that the number of supporting wheels may be increased as may be required to carry the load, and, where necessary, two rails may be provided at each end in place of the single rail shown at each end of the gantry frame.

In the accompanying sheets of drawings,

10 Fig. 1 is a side elevation showing the gantry frame mounted on four wheels for traveling on a runway consisting of two parallel rails, it being understood that the rails need not necessarily be straight but may be curved to the same center;

15 Fig. 2 is a view of one end of the gantry frame;

Fig. 3 is a view of the opposite end;

Fig. 4 is a plan view of the gantry frame on the runway in normal position with its center line at right angles to the rails; and

20 Fig. 5 is a plan view with the frame askew on the runway.

Referring now to the drawings, 10 represents the gantry frame braced to form a rigid structure. The frame here shown has gantry legs 11. The lower ends of the legs are connected together at one end, which, for convenience, will be referred to as the front end, by a sill 12, and at the other or rear end by a sill 13. The frame is supported on two truck sill members, the truck sill at the front end being designated 14 and the truck sill at the rear end being designated 15, each truck sill being here shown mounted on wheels 16 traveling on rails 17, it being remembered that a simplified showing only is made and that the number of rails and wheels may be varied as necessity requires. If desired, the gantry legs can be omitted, leaving only a stiff rectangular frame which is supported on the truck sills.

40 A simple driving unit 18 is shown at one end of each truck sill, each driving unit consisting of a motor connected to a wheel 16 through suitable shafts and gears. The motors are independently controlled, each having a separate controller 45 (not shown).

The gantry frame 10 is supported on the truck sills in the following manner: Secured to the lower end of each leg 11 is a smoothly finished and well lubricated skew plate 19. The skew plate 19 rests upon a similar smoothly finished and well lubricated but smaller skew plate 20, there being between the skew plates 19 and 20 a free sliding surface. The entire weight of the gantry frame and any superstructure mounted thereon is carried on these four sliding surfaces.

Each of the four skew plates 20 is preferably made to rest on a ball or equivalent device to insure equalized pressure between the skew plates 19 and 20. The four balls or equivalent devices of the skew plates 20 engage in socketed members 21 which are secured to the truck sills 14 and 15 near opposite ends thereof.

A straight king pin 22 (see Fig. 3) passes through the frame sill 13 and through the truck sill 15. This pin is located on the center line of both sills and forms a rigid centering and pivot point and transmits the driving force for this end of the frame. It will be keyed in one sill and bushed in the other, as shown at 22a in Fig. 3, thus lending stability to the truck frame, holding it in upright position.

At the opposite or front end of the frame is an offset pin 23 which passes through the frame sill 12 near the center thereof and through the truck sill 14. It is mounted in bushings 23a (see Fig. 2) in the frame sill and in similar bushings in the truck sill so that it will be free to swing to compensate for the relative foreshortening of the center line of the frame as compared to the track gauge and at the same time lend stability to the truck sill as well as transmit the driving force from the truck sill to the frame. It will be noted that the lower end of the pin 23 is mounted centrally of the truck sill 14 while its upper end passes through the frame sill 12 at one side of its center line equal to approximately one-half the distance of the offsetting of the upper end of the pin with respect to the lower end.

When the gantry and its superstructure are traveling along a straight track, both motors 18 will be operated at approximately the same speed. However, when it is desired to skew the frame 10, one motor is slowed down with respect to the other, or, if one of the motors is not operating, the skewing can be done by operating the other motor either in forward or in reverse, depending upon the direction in which the frame is to be skewed, until the desired extent of skewing is obtained. It will be noted that as the skewing occurs the plates 19 secured to the lower ends of the legs 11 will slide smoothly over the lower plates 20. The effect of this skewing is to foreshorten the frame 10 relative to the track span, and this foreshortening is compensated for by the offset pin 23. It will be seen that Fig. 4 shows the frame before the skewing and Fig. 5 shows the frame after the skewing, the extent of foreshortening being equal to the distance between the lines 24 and 25 indicated in Fig. 5.

Thus it will be seen that my invention is admirably adapted for ore unloaders, traveling cranes, and the like, and is useful in any case where skewing of the gantry frame is desirable. Likewise, if the machine or equipment provided with the invention is adapted to travel on tracks whose gauge is greater or less than normal, the inequality in track gauge is automatically compensated for by the free lateral movement of the truck sill 14 relative to sill 12 of the frame.

Likewise, it will be seen that by providing the two operating motors on the truck sills at opposite ends of the gantry frame, all other mechanism for skewing the gantry frame is eliminated.

From the foregoing it will be obvious that the objects stated in the early part of the specification are very effectively attained by the present invention. It is to be remembered that a simplified arrangement only is illustrated, the same, however, showing the preferred construction, but I do not desire to be confined to the precise de-

tails shown but aim in my claims to cover all modifications which do not involve a departure from the spirit and the scope of the invention.

Having thus described my invention, I claim:

5. A gantry including a frame and truck sills with respect to which the frame is movably supported, the truck sills having track-engaging wheels and means for skewing the frame with respect to the sills, said means comprising a vertically disposed straight pin connecting one end of the frame to a truck sill and an offset pin having vertically disposed offset portions connecting the other end of the frame to the opposite truck sill, the first-mentioned end of the frame being always positively centered by the straight pin on the track for the corresponding truck sill.

20. A gantry including a frame and truck sills with relatively slidable plates on the frame and sills by which the frame is movably supported on the sills, and means comprising an offset pin having vertically disposed portions at one end of the frame and connected to one of the truck sills and a vertically disposed straight pin at the other end of the frame and connected to the other truck 25 sill for causing the frame to assume a skewed position with respect to the sills, the sills having track-engaging wheels, the second-mentioned end of the frame being always positively centered by the straight pin on the track for the corresponding truck sill.

30. A gantry including a frame, truck sills and wheels carried by the truck sills, said frame having plates engaging and slidable with respect to similar plates on the truck sills, whereby the

35 frame is movably supported on the truck sills, a straight pin connecting one end of the frame to a truck sill, an offset pin connecting the other end of the frame to the opposite truck sill, and means for skewing the frame with respect to the

40 truck sills, the latter having track-engaging wheels, the first-mentioned end of the frame being always positively centered by the straight pin on the track for the corresponding truck sill.

45. A gantry including a frame, truck sills and wheels carried by the truck sills, said frame having plates engaging and slidable with respect to similar plates on the truck sills whereby the frame is movably supported on the truck sills, a straight pin connecting one end of the frame to a truck sill, an offset pin connecting the other end of the frame to the opposite truck sill, and a separate motor connected to a wheel of each truck 50 sill so that one truck sill may be moved relative to the other to cause skewing of the frame on the truck sills, the latter having track-engaging wheels, the first-mentioned end of the frame being always positively centered by the straight pin on the track for the corresponding truck sill.

55. A gantry including a frame and truck sills with respect to which the frame is movably supported, and means for skewing the frame relative to the truck sills, said means comprising a vertically disposed straight pin connecting one end of the frame to a truck sill and an offset pin connecting the other end of the frame to the opposite truck sill, said offset pin having offset vertically disposed portions, the straight pin being secured in one member and bushed in the other and the offset pin being bushed in both members, the truck sills having track-engaging wheels, the first-mentioned end of the frame being always positively centered by the straight pin on the track for the corresponding truck sill.

60. A gantry including a frame and two truck sills with wheels carried thereby, a straight pin

connecting the center of one end of the gantry frame to one truck sill, an offset pin connecting the other end of the gantry frame near the center thereof to the opposite truck sill, and means for supporting the lower side of each end of the gantry frame on the corresponding truck sill, the truck sills having track-engaging wheels, the first-mentioned end of the frame being always positively centered by the straight pin on the track for the corresponding truck sill.

7. A gantry including a frame and two truck sills with wheels carried thereby, a straight pin connecting the center of one end of the gantry

frame to one truck sill, an offset pin connecting the other end of the gantry frame near the center thereof to the opposite truck sill, and means for supporting the lower side of each end of the gantry frame on the corresponding truck sill, said means comprising plates carried by each end of the gantry frame and engaging corresponding plates carried by the truck sills, the latter having track-engaging wheels, the first-mentioned end of the frame being always positively centered by the straight pin on the track for the corresponding truck sill.
